UNITED STATES PATENT OFFICE.

WALTER LIPPINCOTT, OF PHILADELPHIA, PENNSYLVANIA.

DESIGN FOR A DOOR-BUTTON.

SPECIFICATION forming part of Design No. 28,508, dated April 26, 1898.

Application filed February 24, 1898. Serial No. 671,536. Term of patent 7 years.

To all whom it may concern:

Be it known that I, WALTER LIPPINCOTT, a citizen of the United States, residing at Philadelphia, in the county of Philadelphia and State of Pennsylvania, have invented and produced a new and original Design for a Door-Button, of which the following is a specification, reference being had to the accompanying drawings, forming a part thereof.

10 In the drawings the following views are shown.

Figure 1 is a front elevation of my design for a door-button; Fig. 2, a top view. Fig. 3 is a side view taken from the left side of the button. Fig. 4 is a side elevation taken from the right side of the button. Fig. 5 is a bottom plan view.

The design comprises in outline an L-shaped button, as shown in Fig. 1, having an eye in

the upper end of the upright portion A, and 20 the horizontal portion B is raised on its face in somewhat pyramidal form with a beveled side C, as shown in Figs. 1, 2, 4, and 5, and a triangular-shaped base, as shown in Fig. 5. The back of the button is straight or flat, as 25 shown by Figs. 3 and 4.

Having described my invention, what I claim, and desire to secure by Letters Patent, is—

The design for a door-button substantially 30 as herein shown and described.

In testimony whereof I affix my signature in presence of two witnesses.

WALTER LIPPINCOTT.
